Attorney, Agent, or Firm—Merchant & Gould P.C.

[57]

CLAIM

The ornamental design for slipper, as shown and described.

DESCRIPTION

FIG. 1 is a perspective view of the front, top and side of our new design;

FIG. 2 is a left side elevation view of our new design;

FIG. 3 is a right side elevation view of our new design;

FIG. 4 is a bottom plan view of our new design;

FIG. 5 is a top plan view of our new design;

FIG. 6 is a front elevation view of our new design; and,
 FIG. 7 is a rear elevation view of our new design.

It should be understood that the stitching along the upper edge of the outsole is an ornamental feature of our slipper design.

The broken line showing of the tread in the figures is for illustrative purposes only and forms no part of the claimed design.
